UNITED STATES PATENT OFFICE.

LUC HOUZE, OF MEADVILLE, PENNSYLVANIA.

GLASS-FURNACE.

SPECIFICATION forming part of Letters Patent No. 323,937, dated August 11, 1885.

Application filed March 13, 1885. (No model.)

To all whom it may concern:

Be it known that I, LUC HOUZE, of Meadville, in the county of Crawford and State of Pennsylvania, have invented an Improved 5 Glass-Furnace, of which the following is a specification.

The general object of my invention is to facilitate the use and lessen the cost of gas for heating purposes in glass-furnaces. Hereto- 10 fore it has been manufactured in separate gas-works at an unnecessary waste and expense of fuel; and my special object is to provide glass-furnaces with means for converting the smoke, slack coal, or other fuel into gas by 15 the melting-furnace itself.

Figure 1 of the drawings is a front elevation showing the fire-box, conductor, and connections. Fig. 2 is a transverse vertical section through the conductor and fire-box. Fig. 20 3 is a horizontal section through certain air-flues. Fig. 4 is a transverse vertical section through the melting-chamber and subjacent air-flues.

In the drawings, A represents the melting- 25 chamber of one side of a glass-furnace, the same being provided with the usual melting-pots A'.

B is a fire-box having the hopper b, through 30 which coal or other analogous fuel may be entered. The products of combustion pass up from this fire-box through the hole b' into the median flue of the conductor E; thence, by means of horizontally-partitioned chambers e and the dampers e' e', they may be distributed 35 at a greater or less elevation in the melting-chamber A and with respect to the melting-pots.

A² represents an open space under a brick-arch and on a brick foundation, preferably. 40 B' is a trunk opening into said air-space and hanging in the middle of fire-chamber. At b² it opens into a flue, B², which leads to an air-chamber, B³. From thence the air passes into side flues, e² e², one on each side of 45 the smoke-flue. a represents chimneys connecting with the melting-chamber and a common stack on the top of the apparatus.

C C are two air-flues, which run under the melting-chamber in a longitudinal direction 50 and open at c c into the arched space below,

so as to receive therefrom a supply of air, which passes into the side flues, e² e². From flue e and side flues, e² e², issue products of combustion and hot air, which mix together as they enter the melting-chamber. This new 55 supply of hot oxygen causes a complete combustion of the remaining carbon in said products, and thus utilizes a maximum of the caloric in the fuel.

Thus I make a cleaner gas and at much less 60 expense than is now usual in glass-furnaces.

Having described my invention, what I claim to be new, and desire to protect by Letters Patent, is—

1. In a glass-furnace, the combination, with 55 the melting-chamber A and fire-box B, of the conductor E, having one median and two side flues opening near each other into the said melting-chamber, the median flue connecting with the fire-box and the side flues with an 70 air-supply, as shown, whereby the products of combustion from the fire-box may receive an additional supply of oxygen as they enter the melting-chamber, for the purpose specified. 75

2. The combination, with the melting-chamber A and fire-box B, of the conductor E, having smoke-flue e and air-flues e² e², arranged side by side and discharging into the melting-chamber at the same time, as and for the purpose 80 specified.

3. In a glass-furnace, the combination, with the melting-chamber having melting-pots A' and the fire-box B, of the conductor E, having partitioned chamber e and dampers e' e', 85 whereby the products of combustion may be distributed, as set forth.

4. In a glass-furnace, the combination, with the melting-chamber, of the trunk B', open at b', the flue B², and the flues e² e e², arranged 90 substantially as and for the purpose specified.

5. The combination, in a glass-furnace, with the melting-chamber, of the flues C C, running thereunder, and the flues e² e² in the conductor E, as and for the purpose described.

LUC HOUZE.
